Primary Examiner — Melanie H Tung*Assistant Examiner* — Bao-Yen T Nguyen(74) *Attorney, Agent, or Firm* — Cantor Colburn LLP(57) **CLAIM**

The ornamental design for a display screen or portion thereof with graphical user interface, as shown and described.

DESCRIPTION

The sole FIGURE is a front view a display screen or portion thereof with graphical user interface showing our new design.

The broken lines in the drawing represent the display screen or portion thereof and portions of the graphical user interface and form no part of the claimed design.

1 Claim, 1 Drawing Sheet(56)
